OR D 17,391

UNITED STATES PATENT OFFICE.

GEORGE W. SWETT, OF LANSINGBURG, ASSIGNOR TO SWETT, QUIMBY & CO.,
OF TROY, NEW YORK.

DESIGN FOR AN OIL-STOVE.

SPECIFICATION forming part of Design No. 17,391, dated June 14, 1887.

Application filed May 10, 1886. Serial No. 201,755. Term of patent 7 years.

To all whom it may concern:

Be it known that I, GEORGE W. SWETT, of the village of Lansingburg, county of Rensselaer, State of New York, have invented and 5 produced a new and useful Design for Oil-Stoves, of which the following is a specification.

My invention relates to a design for the shape and surface ornamentation of oil-stoves, and as the same is shown in the accompanying 10 photograph, forming a part of this specification, the several parts of it being indicated by letter reference, and of which the following is a description.

The letter B indicates the stove-body, having 15 an overhanging top T, and this top T is made to have on its outer edge a downwardly and outwardly tapering band-molding, M'.

The letters E designate the sides, and E' 20 the front, the said sides and front being rectilinearly placed with reference to the base and top.

The letter M² indicates a molding in cymatium, that is arranged on the body immediately 25 beneath the overhang of the top, and this molding M² is ornamented with vertical flutings t', and the sides and front are made with the horizontal projecting base-molding f'.

The letters o' designate relief foliated ornaments on the front of the body immediately 30 beneath the overhang of the top, and at each side of the name-plate thereon.

The letters o² designate relief leaf-form ornaments on the body at the front and bottom of the latter, and at each side of the name-plate.

The letters o³ indicate foliated relief ornaments on the front of the body between the 40 doors.

The letter H indicates the stove-base, which laterally projects beyond the body part, and is ornamented on its upper edge with flutings f. The sides S² of the base, and front 45 S³ thereof, taper downwardly and outwardly, with their lower edges scalloped out, as indicated at h', this bottom edge being notched at intervals, as indicated at n. The downwardly and outwardly projecting sides of the 50 base at the corners are laterally and out-

wardly extended, as at b, to form the tops of the feet F, and the latter, where extended laterally from the body, are rounded at the front and projected downwardly and outwardly to the bottom. The doors D close 55 against the stove-front, so as to be in relief thereon, and the door-frames have pilasters p, arranged between the panes, said pilasters being ornamented with relief foliated sprigs m. The door-panes upon the frame N are 60 bordered by a fillet, f², and at the tops are ornamented with a W-form ornament, y, extended downwardly from the top into the pane-areas, and having thereon, as pendent therefrom, a trefoil ornament, i. Each of 65 these doors has two panes; but the number of the panes may be increased or decreased, provided the same ornamentation is applied to them in detail, substantially as described and shown.

Having thus described my design, what I claim, and desire to secure by Letters Patent, is—

1. The design for the shape and ornamentation of an oil-stove, consisting of the overhanging top T, the body B, having the molding M², arranged upon the body beneath the overhang of the top, said molding having thereon vertical flutings, the relief ornaments o' upon the body-front, immediately beneath 75 the top, the relief ornaments o² at the bottom of the front, the relief ornaments o³ on the body, at the front between the doors, the projecting base-molding f' at the front and sides, the laterally-subtending base H, having downwardly and outwardly beveled sides and front with scalloped bottom edges, and the feet F, formed on said base, as shown and described.

2. In a design for an oil-stove, the doors 90 consisting of the frame N in relief upon the stove-body, the pilasters p between the panes and ornamented with the relief foliated sprigs m, and the panes having a bordering fillet, f², and the W-form ornament y, and pendent 95 trefoil figure i at the tops of the panes, as shown and described.

3. In a design for an oil-stove, the shape and ornamentation of the base and feet, consisting of the base H, having the flutings f 100

on its upper surface edge, and having the downwardly and outwardly projected sides S², and front S³, having plain surfaces, with the base at the corners laterally and outwardly extended, as at b, to form the tops of the feet F, and the latter downwardly and outwardly extended from said lateral extension of the base, as shown and described.

Signed at Troy, New York, this 15th day of December, 1885, and in the presence of the two witnesses whose names are hereto written.

GEORGE W. SWETT.

Witnesses:

D. L. HAMILL,
C. H. SHEPARD.
